ABSTRACT

In an hydraulic system a pump draws liquid from a header tank by way of an auxiliary tank which is connected to the header tank, and the discharge from the pump is fed to either tank or partly to each tank under the control of a diverter valve in order to maintain the temperature of the working liquid within desired limits.

HYDRAULIC SYSTEMS

This invention relates to improvements in hydraulic systems employing a liquid such as oil for the transmission of power.

To compensate for the effect of changes in the ambient temperature on the viscosity of the working liquid it is usual, when working in hot weather or in a hot climate, to provide means for cooling the liquid in order to prevent overheating and lubrication failures due to the reduced viscosity of the liquid at high temperatures. On the other hand when low ambient temperatures are experienced the increase in the viscosity of the working liquid leads to increased and unacceptable power losses and possible cavitation at pump suctions.

These difficulties can be mitigated to some extent by using different working liquids in summer and winter, but to change the liquid requires considerable time and labour, and this does not take care of the rapid variations in ambient temperature which can be experienced.

One object of our invention is to provide means whereby the temperature of the working liquid in an hydraulic system is maintained substantially constant independently of climatic conditions.

In an hydraulic system according to our invention a pump draws liquid from a header tank by way of an auxiliary tank which is connected to the header tank, and the discharge from the pump is fed to either tank or partly to each tank under the control of a diverter valve in order to maintain the temperature of the working liquid within desired limits.

The header tank may comprise a radiator located in a relatively exposed position on the vehicle or machine incorporating the hydraulic system. The auxiliary tank is preferably located in a part of the vehicle or machine which is normally warm, as for example an engine bay, and is provided with means such as an electric immersion heater for heating the liquid. This tank may be thermally insulated.

An embodiment of the invention is described as an example and is illustrated in the accompanying drawings, in which:

FIG. 1 is a circuit diagram for an hydraulic transmission system,

FIG. 2 is a diagrammatic representation of the temperature sensitive diverter valve included in the system of FIG. 1, and

FIG. 3 is a sketch of a vehicle incorporating the system of FIG. 1.

One application of the hydraulic system shown is in the transmission system of a vehicle for handling freight containers, known as a straddle carrier and illustrated in FIG. 3. The vehicle has an arched frame 25 supported at each side by a set of hydraulically driven wheels 26 and can straddle a stack of two or, in one version, three freight containers. At the top of the frame there is an hydraulically powered grapple frame (not shown) for lifting and manoeuvring a container. An internal combustion engine 1 on each side of the frame 25 drives hydrostatic pumps 2 and 3 which provide hydraulic fluid for a motor 27 drawing each wheel 26, the pumps and motors being connected in the closed loop hydraulic circuit of FIG. 1.

In FIG. 1 the engine 1 drives variable delivery main pump 2 and a booster pump 3 which keeps the main pump primed and makes good the losses in the system.

The booster pump 3 draws hydraulic liquid from a header tank 4 located high up on the vehicle via an auxiliary tank 5 located in the engine bay. This auxiliary tank 5 is a section of pipe which serves as a junction for a number of hydraulic pipes leading drainage liquid from motors and components back into the system and conveniently provides a reservoir of liquid. An electric immersion heater 6 is provided in this tank for a purpose to be described.

10 The booster pump 3 discharges through a filter 7 having a by-pass 8 to the suction side of the main pump 2. The main pump 2 delivers pressure liquid for the wheel motors and lifting and other hydraulic services on the vehicle via a main hydraulic control valve 9.

15 Surplus liquid from the booster pump 3 is discharged through a relief valve 10 to the inlet of a thermostatically controlled diverter valve 11. The diverter valve 11 has two outlets 12, 13, one 12 connected to the auxiliary tank 5, and the other 13 to the header tank 4. The main pump 2 also discharges via the main control valve 9 and relief valve 10 to the diverter valve 11 when none of the services supplied by it are being operated.

20 One type of diverter valve that can be used is shown in FIG. 2. It comprises a body 14 having an inlet port 15 at one end and outlet ports 12, 13 at the side one above the other. A hollow piston valve 16 is slidable in a bore 17 in the body 14 between extreme positions in which one or the other of the outlet ports 12, 13 is sealed. Between these extreme positions both ports 25 may be open, the extent of their opening being determined by the position of the piston valve 16 in relation to these ports.

25 The piston 16 is connected to one part of a wax-filled thermostatic element 18 and is biased by a spring 19 to a position in which it seals the outlet port 13 to the header tank 4. The element 18 is also engaged by a separate piston 20 slidable in a bore 21 in an end cap 22 of the valve. The position of the piston 20 is regulated 30 by a screwed adjuster 23 so that the temperature setting of the element 18 is adjustable. In this position liquid discharged by the booster pump 3 is returned to the auxiliary tank 5. As the liquid warms up it acts on the thermostatic element which commences to expand and 35 moves the piston 16 so as to open the outlet port 13 to the header tank 4. If the liquid becomes very hot the piston 16 moves to seal the outlet port 12 to the auxiliary tank 5 so that all the fluid is passed to the header tank 4 for cooling before returning to the auxiliary tank 5.

40 If the vehicle is not being used, for example overnight in very cold weather, and it is desired to maintain it in a state of readiness for use, the liquid in the auxiliary tank 5 can be kept at a desired working temperature by the electric immersion heater 6. This insures an adequate supply of warm liquid to keep the main pump system primed, and liquid circulated by the main pump 2 is returned mainly to the auxiliary tank 5 until the liquid in the whole system attains the required working temperature, as determined by the setting of the thermostatic diverter valve 11.

45 If desired the diverter valve 11 can be remotely controlled so that the temperature of the liquid can be sensed at a location remote from the diverter valve 11 and a corresponding signal fed to the diverter valve 11 to produce the necessary proportioning of the return flow to the header and auxiliary tanks 4 and 5.

It will be appreciated that the diverter valve 11 may be located elsewhere in the system. It is however convenient to have it in a section of the system which is subjected to atmospheric pressure so that the header and auxiliary tanks 4 and 5 do not require to be pressurized. If it is desired to pressurise these tanks then the diverter valve 11 may conveniently be located in a part of the system which is subjected to pressure.

It will also be appreciated that the hydraulic systems on each side of the straddle carrier may be interconnected and, in particular, the two header tanks may be connected. In vehicles or machines where it is not practical to locate the header tank in an exposed position, the header tank may comprise a radiator with natural or forced cooling.

The system described above can be incorporated in travelling hoists for freight containers or in any other type of hydraulically powered machine or vehicle for which it is desirable to maintain the temperature and thus the viscosity of the hydraulic fluid substantially constant.

We claim:

1. A vehicle for handling freight containers, said vehicle comprising an arched frame, a set of wheels sup-

porting each side of the frame, and engine on each side of the frame, a main pump and a booster pump driven by each engine, the wheels of each set being driven by pressure liquid from the main pump, an auxiliary tank 5 from which the booster pump draws liquid for supplying the suction side of the main pump, a header tank connected to the auxiliary tank means for maintaining a difference in temperature between the liquids in each tank, a diverter valve having an inlet port connected to 10 the discharge side of the main pump, an outlet port connected to the auxiliary tank and a second outlet port connected to the header tank, and a temperature sensitive element arranged in the liquid discharged from the main pump to control the operation of the diverter valve whereby the liquid from the main pump is directed between the auxiliary and header tanks in accordance with the temperature of the liquid to maintain the temperature of the working liquid within desired limits.

2. A vehicle as in claim 1 wherein the auxiliary tank is located near the engine and the header tank is located higher up on the frame.
